LINING PAD

Jack R. Roland, San Francisco, Calif., assignor
to Illinois Pacific Coast Company, San Fran-
cisco, Calif., a corporation of Delaware

Application September 21, 1931
Serial No. 563,951

4 Claims. (Cl. 217—3)

This invention relates to lining pads such as employed in packing boxes, crates, and the like, which are used for the purpose of cushioning and protecting the contents against chafing and bruising or becoming otherwise damaged, the invention relating in particular to a pad which is employed as a liner and cushioning material for fruit boxes during shipment and transportation of pears, apples and like fruits.

10 Pears and like fresh fruits, after picking, are usually graded, cleaned and wrapped in tissue paper and are then snugly packed in boxes for transportation to the market. Actual experience has demonstrated that the outer layers of fruit 15 are subject to damage by box cutting, chafing, bruising, etc., hence the necessity of employing a lining or cushioning pad to protect the fruit. The pads employed are usually excelsior pads, corrugated paper pads, etc., and these are placed 20 in the bottom, the sides, and the ends of the box. The fruit is then packed and a top pad is placed on top of the fruit when the box is full. A lid is then nailed in place and the packing operation is completed. After the pads are placed in a 25 box the sides and particularly the end pads have a tendency to bend inwardly and as such are a source of inconvenience and annoyance to the packers, particularly while the first layer or two is being placed in position, causing serious delay 30 and expense.

The object of the present invention is, accordingly, that of generally improving and simplifying the construction and operation of lining pads, such as employed for pears, apples, and like 35 fruits, and more specifically stated to provide a lining pad in which the several sections and particularly the end sections are interlocked when placed in the box so that inward bending movement is prevented and a smooth lining surface is 40 presented which will not interfere with the packers when packing the fruit.

The invention is shown by way of illustration in the accompanying drawings, in which—

Fig. 1 is a plan view of a pad in flat or unfolded position, the pad shown being a combination bottom, side and end pad.

Fig. 2 is a perspective view showing the combination bottom, side and end pad in folded position and ready for insertion in the fruit box.

Fig. 3 is a plan view of a combination side and end pad.

Fig. 4 is a perspective view of the combination side and end pad folded and ready for insertion in the fruit box.

Fig. 5 is a cross section of the cushioning mate-

rial from which the lining pads are manufactured.

Referring to the drawings in detail and particularly Fig. 1, a protective pad for insertion as a lining for fruit boxes is shown. The lining pad 60 consists of a sheet of cushioning material and it is scored along the lines indicated at 2, 3, 4, 5, 6 and 7 to permit it to be folded to form a bottom pad A, two side pads B, and four half end pads such as indicated at C.

The material forming the sections corresponds to the size of the bottom, sides and ends respectively of the box for which it is intended and, when it is to be used, it is folded along the lines indicated at 2 to 7, inclusive, to assume the shape 70 shown in Fig. 2 and in this position it is placed directly in the box. During the folding of the pad from the blank or flat form shown in Fig. 1, the end sections in particular tend to spring 75 inwardly when placed in a box and in order to prevent this and to retain the side and end sections of the pad in snug engagement with the sides and ends of the box, interlocking lugs such as shown at 8 are formed on the lower ends of 80 the half end sections. These lugs are inserted between the ends of the bottom pad A and the ends of the box and as such form an interlock which secures the end sections and the sides in 85 snug engagement with the surfaces of the box. With the lining pads thus positioned and secured in the box the packer is ready to place the fruit one layer after another in the box until 90 it is completely filled and, as the end or side sections do not tend to spring inwardly, the packer is not annoyed nor does he or she lose any time in placing and packing the fruit.

In Figs. 1 and 2, the entire lining is connected, that is, the side sections B are connected to the bottom section A and the end sections C are in turn connected to the side sections B. This structure while convenient is not necessary. For instance, by referring to Figs. 3 and 4, it will be noted that the side and end sections may be entirely independent of the bottom pad. In these drawings, D indicates the side sections of the pad and E the end sections. The material is scored along the lines indicated at 9 and it may accordingly be folded ready for insertion in the box in the manner shown in Fig. 4. When a pad is made as shown in Figs. 3 and 4, a separate bottom pad is employed. This is first placed in the bottom of the box and the connected side and end sections shown in Fig. 4 are then placed in the box. Lugs such as indicated at 10 are then 105 interlocked with the ends of the bottom pad and 110

as such secure or hold the end and side pads in snug engagement with the ends and sides of the box.

Any suitable cushioning material may be employed but the preferred form of material is that shown in Fig. 5. Corrugated paper such as indicated at 11 is employed and on the inner side thereof is pasted or otherwise secured a sheet of cardboard or the like such as shown at 12. This material forms an ideal cushioning or lining pad for fruit boxes but other materials may obviously be employed.

While certain features of the present invention are more or less specifically described, I wish it understood that various changes may be resorted to within the scope of the appended claims. Similarly, that the materials and finish of the several parts employed may be such as the manufacturer may decide, or varying conditions or uses may demand.

Having thus described my invention, what I claim and desire to secure by Letters Patent is—

1. A protective pad for insertion as a lining for fruit boxes comprising a pad of cushion-like material adapted to be folded to form a bottom and two side sections, said sections corresponding in size to the bottom and sides of the box for which it is intended, a half end section at each end of each side section and foldable to cover the ends of the box, and a lug on each half end

section adapted to interlock with the ends of the bottom pad and hold the side and end sections of the liner against the sides and ends of the box.

2. A protective pad for insertion as a lining for fruit boxes comprising a pad of cushion-like material adapted to be folded to form a side and two half end sections, said sections corresponding in size to the side and half of each end of the box for which it is intended, and a lug on each half end section engageable with the ends of a bottom pad inserted in the box to hold the ends and the side section of the lining pad against the side and ends of the box. 80

3. A pad for lining a box which comprises a bottom section, side sections adapted to be bent up from the bottom section and end sections adapted to be bent in from the side sections, said end sections having portions abutting the ends of the bottom section whereby they will be engaged between said bottom section and the ends 90 of the box. 95

4. A lining pad for fruit boxes which comprises a bottom section, side sections, end sections bent from the ends of the side sections, and portions on said end sections projecting downwardly 100 below the top surface of the bottom section whereby the bottom section will prevent movement of the end sections inwardly from the walls of the box. 105
